LIQUID DISPENSER

William A. Gabriel, Oakland, Calif., assignor to
Sanitary Vending Company, San Francisco,
Calif., a corporation of California

Application April 10, 1937, Serial No. 136,043

10 Claims. (Cl. 221—94)

The invention relates to devices arranged for dispensing small quantities of substances and of the type frequently provided in public places and the like for dispensing soaps, oils and other liquids or fluids or solids.

An object of the invention is to provide a dispenser of the character described which is particularly designed for use in public places and provides a very attractive device and an attractive display of the material to be dispensed, which in accordance with the present invention, is contained in standard size bottles or packages as marketed by the manufacturer of the material.

Another object of the invention is to provide a dispenser of the character described which will be simple and compact in form and will have incorporated in the operating mechanism thereof a coin operative mechanism, the entire device being constructed of a minimum number of simple and ruggedly constructed operating parts which will give positive and continuous service for a long substantially indefinite period of time.

A further object of the invention is to provide a device of the character described, which may be quickly and readily opened by the attendant for replacing a bottle or other container of substances to be dispensed and for the removal of the coins deposited by users in the operating of the dispenser.

Still another object of the invention is to provide a dispenser of the character described which may be readily adapted for use with various shapes and sizes of material containers to be used with the dispenser.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings:

Figure 1 is a front elevation of a dispenser constructed in accordance with the present invention.

Figure 2 is a front view similar to Figure 1 but shown with a portion of the outer casing cut away to illustrate the internal operating parts.

Figure 3 is a transverse plan sectional view of the dispenser and is taken substantially on the plane of line 3—3 of Figure 2.

Figure 4 is a fragmentary vertical sectional

view of the dispenser and is taken substantially on the plane of line 4—4 of Figure 1.

Figure 5 is a rear elevation of the dispenser as shown in Figure 1.

Figure 6 is a side elevational view partly in cross section showing the mounting construction.

Figure 7 is an enlarged sectional view of the dispenser pump.

A dispenser embodying the present invention is illustrated in the accompanying drawings and comprises an outer casing 6 having a front wall 7, side walls 8 and 9, a top wall 11 and a bottom wall 12 below which the casing is reduced in depth to define a portion 13. Mounted on the inner side of a board 16 and within the casing 6 is a supporting plate 17 on which the operating mechanism is mounted and, in accordance with the present invention, the back board 16, together with the casing and mechanism is adapted to be secured as a unit to a wall 19 or the like, by the use of a mounting plate 18 which is arranged to be screwed as at 20 or otherwise affixed to the wall and is provided at its upper end with a pair of pins 21 which are extendable through openings 22 in the board 16 and through openings 23 in the plate 17 and are provided at their outer ends with heads 24 which are arranged to slide into and lock with slots 26 provided in the plate 17 at the outer side of the openings 23, the plate 13 being adapted to fit in to a recess 27 provided in the back side of the board 16 so that the latter will abut directly against the wall 19 and prevent access to the supporting parts from the sides and back of the mounting board 16. The lower end of the assembly is secured together by means of a screw type barrel lock 28 which is mounted through the front wall of the casing 13 and is extended through openings 29 and 31 in the plate 17 and board 16 for threaded engagement in a socket 32 provided on the wall plate 18. Thus on removal of the lock 28 the unit may be removed from the wall plate 18 by lifting the back board 16 sufficiently to release the headed projections 24 from the slots 26. In the present construction the casing is secured to the back board 16 by means of a plurality of studs 33 affixed to the casing and extended through openings 34 in the back board 16 and secured to the board by nuts 36 mounted in recesses 37 in the back side of the board. Removal of the casing from the board may therefore be effected by loosening the nuts 36 and drawing the casing forward from the board 16.

The operating mechanism of the dispenser, as above referred to, is substantially completely car-

ried by the plate 17 and includes a bottle 35 or container for material to be dispensed; a dispenser or pump unit 38 connected to the bottle; a manually controlled operating arm 39 which 5 extends through an opening 41 in the side 9 of the outer casing and is provided with a knob 42 to facilitate its manual movement into and from the casing; and a coin controlled lock 43 operatively connected between the arm 39 and the pump 38 so as to connect the arm and pump upon insertion of a coin to enable dispensing of fluid from the bottle by operation of the arm 39.

The dispensing unit 38 here used, comprises a casing 44 provided at the top thereof with a seat or socket 46 for the open neck end 47 of the bottle 35 and is provided below the seat with a dispenser pump cylinder 49, communicated with the socket by a passage 48. Reciprocally mounted in the cylinder 49 is a plunger 51 which on 10 movement into the cylinder is adapted to discharge fluid contained therein from a discharge port 52 provided in the bottom of the casing 44. As will be seen from Figure 4, the pump or dispenser unit 38 is mounted forwardly of the back 15 plate 17 by means of a bracket 53 and is positioned with the discharge port 52 above an opening 54 in the bottom wall 12 of the casing, the wall 12 being preferably provided with a depending wall portion 56 surrounding the opening 54 20 to prevent access to the dispenser mechanism. An air inlet tube 57 is supported in the seat 46 and is communicated with the atmosphere at its lower end by an air inlet opening 58 and is extended to substantially the top of the inverted 25 bottle 35 to allow entry of air into the bottle to replace the fluid discharged. The bottle is supported in inverted position with the open neck end 47 thereof securely held in the seat 46 and with the lower end of the neck compressed 30 against a gasket 59 in the seat, by means of a bracket 61 secured to the upper end of the plate 17 and clamped against the end 62 of the bottle by means of a set-screw 63.

As an important feature of the dispenser unit 45 I provide opposite the discharge port 52 a pivoted closure 64 therefor which is rotatable on a stem 66 to and from a position against and closing off the discharge opening. Actuation of this closure member is designed to be automatically effected in the operation of the dispenser and to this end the stem 66 is preferably connected to the manually movable member 39, such as by means of a gear 67 on the stem and a rack 68 on the arm 39 as here shown, so that on movement of the arm 39 to discharge liquid, the closure will be automatically withdrawn from the discharge port and on release of the arm 39 following such discharge the closure will be automatically withdrawn from the discharge port and 55 on release of the arm 39 following such discharge the closure will be automatically returned to a position sealing off the discharge port. Also preferably the closure is provided with a projection 71 which is extendable into the discharge passage 52 and to prevent any drying or caking of the liquid in or about this discharge passage as might interfere with the proper operation of the device.

As previously stated, connection of the operating arm 39 with the pump plunger 51 is effected 70 through a coin controlled mechanism 43 which is effective to normally maintain these parts disconnected and to provide an operative connection therebetween only on insertion of a proper 75 coin. The mechanism here consists of a stationary

mounting plate 73 arranged forwardly of the back plate 17 and within which is slidably mounted a box-like carriage 74 having opposed vertical sides 76 and 77 slidably engaged with the stationary plates 17 and 73. Carried by a shaft 75 journaled in the plates 17 and 73 at a point below the carriage 74, is a lever 78 which extends up through the carriage between the sides 76 and 77 thereof and is normally freely movable with respect thereto. The carriage is, in the present construction, connected to the plunger 51 of the dispenser while the lever 78 is connected to the operating arm 39 so that normal reciprocation of the arm 39 will only cause a free reciprocation of the lever 78 within the carriage 15 74 and no movement of the plunger will be effected. The operative connection between the lever 78 and the carriage 74 and therefore between the arm 39 and the pump is effected by a coin 79 which may be inserted through a coin 20 slot 81 in the top wall of the casing and is arranged to fall with the opposite peripheral portions thereof into opposed recesses 82 formed in the inner surfaces of the carriage sides 76 and 77 and is normally supported in the recesses on a shoulder 83 on the lever 78. Thus the inserted coin lies directly across the interior of the carriage 74 and blocks the movement of the lever 78 therethrough and consequently causes a transverse movement of the carriage under the urge of the lever 78 when the latter is operated by the arm 39. At the end of the movement, however, determined by the engagement of a stop 84 on the lever 78 with a pin 86 carried by the plates 17 and 73, the shoulder 83 is rotated to 30 an inclined position such as to release the coin from between the carriage and the lever 78 for deposit in the coin box 87 positioned in the casing. On release of the arm 39 the lever 78 is returned to a starting position by means of a spring 88 connected thereto while the carriage is similarly returned to the starting position by the resilient expansion of the pump plunger 51.

Connection of the carriage with the plunger is effected by means of a lever 89 pivoted to a shaft 45 91 carried on the mounting plate 73 and which is pivotally and slidably secured at its lower end 93 to the plunger and similarly connected at its upper end 94 to a transverse pin 96 secured to the carriage wall 77 and extended through a slot 97 50 in the mounting plate 73. The operative connection between the arm 39 and the lever 78 here consists of a lever 98 which is pivoted intermediate its ends to the shaft 91 and is arranged at its lower end 99 to abut the inner end 101 of 55 the arm 39 and is connected at its upper end 102 by means of a slip joint 103 to an arm 104 secured to the shaft 75 of the lever 78. Thus on insertion of a coin to establish an operative connection between the lever 78 and the carriage 60 74, an inward movement of the arm 39 will cause a clockwise rotation of the lever 98, as viewed in Figure 2, which will in turn, cause a counter-clockwise rotation of the lever 78 and an advancement of the carriage and upper end of the 65 lever 89 from right to left, as viewed in said figure, with a corresponding movement of the plunger from the left to right and into the pump cylinder of the dispenser.

As an important feature of the present dispenser I embody in the dispenser bottles or other containers for the materials to be dispensed which are of a standard size and shape as marketed by the manufacturer of the product being dispensed and so arranged the container in the 75

apparatus as to permit a full and attractive display of one side of the container. This is effected by the use of an opening or window 106 in the front wall 7 of the casing directly opposite the bottle 35 and the forward positioning of the bottle within the casing so as to dispose one side 107 of the bottle in the opening and against the forward side 7 of the casing. In accordance with the present arrangement of the device, the opening is of sufficient size to expose the entire side 107 of the bottle or at least, the whole or a substantial part of a label 108 provided on the side 107 of the bottle. Furthermore, the peripheral edge of the opening 106 is so cut as to closely fit the rounded corners 109 of the bottle so as to cause a slight forward protrusion of the bottle side 107 into the opening and into substantially flush relation with the outer side of the forward wall 7 of the casing. In this manner, the bottle itself forms a closure for the opening and a part of the forward wall of the casing.

In order to make the casing readily adaptable for use with different sizes and shapes of bottles, I provide in the opening 106, a frame member 111 which is formed separately from the casing and is arranged for positioning and fixing in a peripheral recess 112 formed in the outer side of the forward casing wall 7 around the opening 106, with the forward surfaces of the frame substantially coplanar with the forward surface of the wall 7. Thus I may use a standard and identical casing for dispensers using bottles of various sizes and shapes by providing a different frame member for each size and shape of the bottle to be used, each of the different frames having a standard peripheral size for securing to the casing, as above mentioned.

I claim:

1. A liquid dispenser of the character described comprising, a casing, a bottle polygonal in cross section mounted in said casing for containing liquid to be dispensed, means connected to said bottle for dispensing liquid therefrom to the exterior of said casing, said casing being provided with an opening in the front wall thereof, and said bottle being mounted with substantially an entire side thereof exposed in said opening.

2. A liquid dispenser of the character described comprising, a casing, a liquid container mounted in said casing, means connected to said container for dispensing liquid therefrom to the exterior of said casing, said casing being provided with an opening in an exposed wall thereof, and said container being mounted with a side thereof extending into said opening.

3. A liquid dispenser of the character described comprising, a casing, a liquid container mounted in said casing, means connected to said container for dispensing liquid therefrom to the exterior of said casing, said casing being provided with an opening in an exposed wall thereof, and said container being mounted with substantially an entire side thereof extended into said opening in substantially flush relation with the outer side of said casing.

4. A liquid dispenser of the character described comprising, a casing, a liquid container mounted in said casing, means connected to said container for dispensing liquid therefrom to the exterior of said casing, said casing being provided with an opening in an exposed wall thereof, and said container being mounted with a side thereof extended into and forming a closure for said opening.

5. A liquid dispenser of the character described comprising, a casing, a bottle mounted in said casing and adapted to contain liquid to be dispensed, dispensing means connected to said bottle for discharging liquid therefrom to the exterior of the casing, said bottle having sides and rounded corners, and said casing having an opening of substantially the size of one of said bottle sides and having a peripheral edge of said opening engaged on the rounded corners of said bottle to substantially seal said bottle in said opening.

6. A liquid dispenser of the character described comprising, a casing provided with an opening in an exposed wall thereof, a bottle mounted in said casing and adapted to contain liquid to be dispensed and positioned with a side thereof in said opening, manually controlled dispensing means connected to said bottle for discharging the contents thereof to the exterior of said casing, and a frame mounted around said casing opening for engagement with said bottle.

7. A liquid dispenser of the character described comprising, a casing provided with an opening in an exposed wall thereof, a bottle mounted in said casing and adapted to contain liquid to be dispensed and positioned with a side thereof in said opening, manually controlled dispensing means connected to said bottle for discharging the contents thereof to the exterior of said casing, said casing being provided with a recessed seat surrounding said opening, and a frame mounted in said seat for engagement with said bottle.

8. A liquid dispenser of the character described comprising, a casing provided with an opening in an exposed wall thereof, a bottle mounted in said casing and adapted to contain liquid to be dispensed and positioned with a side thereof in said opening, manually controlled dispensing means connected to said bottle for discharging the contents thereof to the exterior of the casing, said casing being provided with a seat surrounding said opening at the outer side of said casing, and a frame mounted in said seat for engagement with said bottle and extending into flush relation with the outer surface of said casing.

9. A liquid dispenser of the character described comprising, a casing, a liquid container mounted in said casing, dispensing means supported by said casing and connected to said container and provided with a reciprocally movable dispensing valve and a discharge port, manually displaceable means connected to said valve, and closure means for said port and mounted for movement to and from a position closing said port and being connected to and movable by said manually displaceable means for automatically opening said port upon actuation of said means in one direction and to close said port upon actuation of said means in a reciprocal direction.

10. A liquid dispenser of the character described comprising, a casing, a liquid container mounted in said casing, dispensing means connected to said container and provided with a movable displaceable means connected to said valve, closure means pivoted to said dispensing means and rotatable to and from a position closing said port, a gear connected to and rotatable with said closure means, and a rack movable by said manually displaceable means and connected to said gear.

WILLIAM A. GABRIEL.
